United States Patent

Des. 234,305
Patented Feb. 11, 1975

234,305

BICYCLE EXERCISER

Thomas G. Woods, Percy A. Collins, and Lewis W. Boyd,
Battle Creek, and Bruce G. Remington, Kalamazoo,
Mich., assignors to Battle Creek Equipment Co., Battle
Creek, Mich.

Filed Aug. 18, 1972, Ser. No. 281,931

Term of patent 14 years

Int. Cl. D21—02
U.S. Cl. D34—5 K

FIG. 1 is a front perspective view of a bicycle exerciser showing our new design;

FIG. 2 is a rear perspective view thereof;

FIG. 3 is a left side elevational view thereof.

We claim:

The ornamental design for a bicycle exerciser, substantially as shown.
